UNITED STATES PATENT OFFICE.

FRANK FLEMING, OF ROCKFORD, ILLINOIS.

BUILDING-DIRECTORY.

No. 895,357.

Specification of Letters Patent. Patented Aug. 4, 1908.

Application filed October 10, 1907. Serial No. 396,853.

To all whom it may concern:

Be it known that I, FRANK FLEMING, a citizen of the United States of America, residing at Rockford, in the county of Winnebago and State of Illinois, have invented certain new and useful Improvements in Building-Directories, of which the following is a specification.

My invention relates to a building directory particularly intended for use in office buildings where there are numerous tenants, and where it is desired to provide a directory in such form that the names therein may be changed as often as necessitated by changes of tenants; and it consists of certain new and useful features of construction and combinations of parts especially devised to that end, all as hereinafter fully described and specifically pointed out in the claims.

20 Referring to the accompanying drawings, which form a part of this specification, Figure 1 is a front view of a directory embodying my improvements. Fig. 2 is a section, at the dotted line 2—2 in Fig. 1, of parts 25 there shown. Fig. 3 is a like view of the same, with parts wanting and other parts in different positions. Fig. 4 is an isometrical detail view of one of the clamping-leaves of the directory. Fig. 5 is a section, at the 30 dotted line 5—5 in Fig. 1, of parts there shown with other parts wanting. Fig. 6 is a like view of the same, with parts in different positions.

Like reference characters indicate corresponding parts throughout the several views.

35 7 and 8 are the side pieces, and 9 and 10 the top and bottom pieces, of the frame. The two latter have recesses 11 formed therein for the reception of parts to be described 40 hereinafter. The parts of the frame may be secured together in any suitable manner and have a back 12 securely attached thereto. The united parts just described constitute a holder for the remaining parts of the directory.

45 13 are clamping-leaves pivotally mounted within the holder substantially parallel to the back 12 thereof and to each other. These leaves are shown as being mounted by means 50 of pintles 14 thereon inserted into sockets 15 in the parts 9 and 10, but they may obviously be pivoted into the holder in any other available and desired manner, the only requisites being that they shall occupy the proper relative 55 positions to the back of the holder and to each other and be adapted to be opened

outward to admit the name-plates, to be described, and closed upon their end portions to clamp them against the back of the same.

16 are springs shown as secured between 60 the parts 9, 10 and 12 and as projecting their operative portions into the recesses 11 in said parts 9 and 10. These springs normally maintain the leaves 13 closed upon the end portions of the name-plates, to be described, 65 and clamp the same against the back 12 of the holder, as in Figs. 1 and 5.

17 are name-plates, which are preferably composed of thin flexible strips of pasteboard. Upon these plates the desired names 70 and numbers may be marked in any suitable manner.

18, 19, 20 and 21 are the top, bottom and side pieces of a frame which is glazed with a sheet of glass 22. The parts just described 75 constitute the closure, of the holder, which is of proper dimensions to be slid into and seated in the rectangular opening 23 in the front of the same, where it may be secured in any desired manner.

80 Supposing the closure of the holder to be removed therefrom and the clamping-leaves 13 to both be opened to the position shown by the left hand leaf 13, in Fig. 6, the name-plates 17 are then placed against the back 12 85 of the holder and the leaves 13 are swung in against the end portions of the same, Figs. 1 and 5, where they will remain securely clamped by the action of the springs 16. Obviously the leaves 13 may be opened whenever desired and the name-plates in the directory be changed or rearranged in any desired manner.

90 What I claim as new, and desire to secure by Letters Patent, is—

95 In a directory of the class described, in combination, a frame and back therefor constituting a holder, clamping-leaves pivotally mounted within the holder substantially parallel to the back thereof and to each other, 100 name-plates and springs normally maintaining the leaves closed upon the end portions of said name-plates and clamping the same against the back of the holder.

105 In testimony whereof I have signed my name to this specification in the presence of two subscribing witnesses.

FRANK FLEMING.
